MILLING MACHINE

Filed May 8, 1928

UNITED STATES PATENT OFFICE

THEODORE EARLE, OF DENVER, COLORADO

MILLING MACHINE

Application filed May 8, 1928. Serial No. 276,015.

My invention relates to milling machines, more especially to such machines which are adapted to handle conglomerate or other substances including constituents of different hardness, and the separation thereof, whereby my process may be carried out, and is an improvement over my former invention, application for Letters Patent on which was filed April 20th, 1928, the serial number being 271,504.

In my former invention and process the material treated was subjected to a rubbing action between two relatively moving and intermittently separating rubbing surfaces and thereby the softer material was rubbed free of association with the harder material, the harder material temporarily sinking into one of the rubbing surfaces to avoid being crushed, splintered or powdered, one of the surfaces being reciprocated vertically, the other surface being reciprocated horizontally, or at an angle thereto.

That is, the rubbing surface upon which the material is supported is reciprocated, as is also the rubbing surface co-acting therewith.

In some materials, under some conditions, the reciprocation of the material being treated may produce results not desired; and in large units, the reciprocation of the lower rubbing surface with all the material it may hold tends toward an unwieldy and costly machine.

The object of my present invention is to provide a machine for treating and separating such conglomerate substances as mentioned above, in which the constituents of the substance are disassociated by being rubbed intermittently between a stationary rubbing surface and a movable rubbing surface, and subsequently separated.

My present invention consists in a machine for intermittently rubbing the material along a stationary rubbing surface by a movable rubbing surface of either equal or unequal hardness, the movable surface intermittently raising from the stationary surface, the intermittent action thereby produced acting to rub the softer material from association with the harder material of the substance; the crush-

ing, splintering, or powdering of the harder material being prevented either by well regulated pressure between the surfaces or by the harder material temporarily sinking into one or the other or both of the rubbing surfaces depending on details selected for each case; the intermittent action providing a cooling effect on the material and the surfaces, and also assisting in the disassociation of the constituents of the conglomerate substances treated, and the stationary rubbing surface supporting the material providing a stationary period for the material which permits the same to settle and come to rest between the contacts of the movable rubbing surfaces.

The constituents of the conglomerate substance are next separated, which separation is a part of my process, though it may be performed in some cases hydraulically, at the time of the disassociation of the constituents, in which case the rest period of the material provided in this invention between the contacts of the movable surfaces is of considerable advantage under some conditions and with some materials.

Or, the separation may be made by the dry method, when it is performed subsequently to the disassociation stage, except in the case of some special substances as noted below.

If performed subsequent to the disassociation stage, the separation may be made by any of the air and gravity methods, or hydraulically, ionically, chemically, electrically, magnetically, electrostatically, or in any other well known or proper manner.

But, since the various devices and methods by which the constituents may be separated after their dry disassociation are no part of this invention, they are not shown nor further described in detail herein.

The construction of the device whereby the above process may be put into operation is shown in the drawing, in which:—

Figure 1 is a side elevation in partial section of the preferred form of my device, adapted for dry operation.

Figure 2 is a fragmentary section showing the machine adapted for wet operation.

Figure 3 is a plan view of Figure 2, but

also showing a plan view of the feed bin and grizzly plate shown in Figure 1.

In the form shown in Figure 1, the frame 1 supports the stationary rubbing surface 2, which forms the bottom of the tank having walls 3, tied together at the lower end by the cross piece 3'.

The upper portion of the bottom 2 is shown composed of rubber or similar material, while 10 the lower portion is composed of metal, which will be explained more in detail below.

Upon the tank and frame is properly mounted and journaled the drive shaft 4, upon which is mounted the driving and free 15 pulleys 5 and 6, respectively, and the driving gear 7. The cam shaft 8 is also properly mounted and journaled on the tank and frame.

Upon the cam shaft 8 is securely mounted 20 the cam shaft gear 9, the crank pin 10 and the cam 11.

Thus, the rotation of the driving pulley 5, which is driven by a belt, rotates the cam shaft 8, the speed and torque being changed 25 by the relative sizes of the gears 7 and 9.

The cam roller 12, mounted by the pin 13 on the cam lever 14, rolls upon the cam 11 and thereby oscillates the cam lever 14 about its mounting pin 15. Upon the vertical arm 30 16 of the cam lever 14 is pivotally mounted the adjustable connecting rod 18 by the pin 17.

The rod 18 is pivotally connected by the pin 20 to the vertical arm of the bellcrank 19, which is pivotally mounted on the pin 21. 35 The pin 21 is secured in the short bifurcated arms of the bellcrank 22, which is pivotally mounted on the pin 23.

The pin 23 is securely mounted on the standard 24 which is carried by the tank and 40 the frame 1.

The long arm of the bellcrank 22 is attached to one end of the cable 25, the other end of which is attached to the drum 26, which is mounted to rotate with the worm gear 27, 45 adjacent the shaft 4.

The worm 28 is mounted to mesh with the worm gear 27 and to be revolved by the handle 29.

Thus the handle 29 may be used to revolve 50 the drum 26 and wind the cable 25 thereon, which will raise the short arms of the bellcrank 22 and thus raise the bellcrank 19, for purposes which will be explained later.

The muller frame 30 is provided with the 55 brackets 31 and 32.

The brackets 32 are pivotally mounted by the substantially U-shaped hanger 33 upon the horizontal arm 34 of the cam lever 14.

Each leg of the hanger 33 is provided with 60 an out-turned pivot end adapted to be received in the slot of the brackets 32.

The slotted construction of the brackets 32 permits vertical self adjustment of the upper end of the muller frame 30 as will be taken 65 up more fully later on.

The brackets 31 are pivotally mounted by the pin 35 upon the slotted hanger 36, which is pivotally mounted by the pin 37 upon the horizontal arm of the bellcrank 22.

The slotted construction of the hanger 36 70 permits vertical self adjustment of the lower end of the muller frame 30 as will be more fully explained later on.

It will now be seen that the mechanism controlled by the worm handle 26 may be used 75 to vary the height of the lower end of the muller frame 30.

Attached to the muller frame 30 are the brackets 40 upon which the connecting rod 41 is pivotally mounted by the pin 42.

As the cam shaft 8 revolves, the action of the cam roller 11, roller 12, roller lever 14, arms 16 and 34, connecting rod 18, bellcranks 19 and 22 and hangers 36 and 33, will raise 85 and lower the muller frame 30 once every revolution.

And as the crank pin 10 revolves with the shaft 8 the action of the connecting rod 41 and pin 42 will reciprocate the muller frame 30 once every revolution.

The mullers 43 are suspended from the muller plate spindles 44.

The spindles 44 are screwed into the mullers 43 and locked in place by the lock wire 45, see 90 Figure 3.

The upper ends of the spindles 44 are flanged and are also provided with the holes 46 for use in adjusting the height of the spindles in the mullers 43, and for locking the spindles in place by use of the lock wire 45.

The cushion cup 47 may be of one piece construction or built up as shown, and is attached to the muller frame 30 by the bolts 48 and nuts 49. The bottom of the cup is provided with large apertures through which 100 pass the spindles 44.

The muller cushion 50 preferably of live rubber fits in the cushion cup 47 and surrounds the muller spindle 44.

The muller cushion may, if desired, be 110 made of any other proper material or construction, such as a steel spring, a pneumatic cushion, or other equivalent, so long as the final result will be the proper cushioning of the impact between the muller frame 30 and the mullers 43 when the rise of the frame lifts the mullers from the stationary surface 2.

To the lower face of each muller 43 is attached the muller plate 51, preferably of rubber, though it may be made of any other 120 proper material, or even integral with the muller 43, and its hardness may be either different from, close to, or identical with that of the stationary rubbing surface 2, depending upon the material, the requirements, and other conditions.

The tank bottom, or lower, or stationary rubbing surface 2, may also be of any suitable material and its hardness may be different from, close to, or identical with that of the 130

muller plates 51. But, though the tank bottom 2 and the muller plates 51 may be varied in material as stated, I believe in the majority of cases the bottom will be made of steel or other metal, rubber, or wood, and the muller plates will be made of rubber, wood, metal or other suitable material.

With some material under some conditions, it has been found that both rubbing surfaces 10 may be of the same hardness provided they are both of slightly compressible material.

In fact there are some cases where both surfaces may even be substantially non-compressible and of the same hardness, the crushing, splintering and powdering of the material being controlled by regulation of the pressure between the surfaces.

But, for the majority of cases, and for trouble-proof operation when in the hands 20 of careless, ignorant, or incompetent operators, the surfaces of unequal hardness or surfaces at least slightly compressible will be found to be most satisfactory.

As shown in Figure 1 the upper end of the 25 machine is provided with surfaces of equal hardness and compressible, while the lower end of the machine is provided with surfaces of unequal hardness, one being compressible.

This combination, while it may give good 30 results with some materials, requirements, and conditions, may not be satisfactory in other cases.

But the combination is shown to give an 35 indication of the flexibility of my process and machine in being adapted to give the results desired.

As shown, the muller plates 51 are attached 40 by a plural dovetail construction to the mullers 43, but any other suitable means of attachment may be employed provided it gives the same reliable result.

The spindles 44 are positioned slightly 45 forward of the center of gravity of the mullers 43, so that when they are lifted from the bottom 2, the lower end of the muller will tend to hang slightly lower than the upper end thereof, and thus be substantially parallel with the slope of the bottom 2. But, the hang of the mullers and the pressure 50 between the surfaces may be varied as desired by the addition of weights such as shown at 52, which are attached to the mullers by the bolts 63, or may be attached in any other proper manner.

The position of the mullers on the muller 55 frame 30 may be changed by loosening the nuts 49 and sliding the cups 47 to the desired position.

And the hang of the mullers and their 60 weights can be made as desired by the proper position, number and size of weights such as shown at 52.

In operation the material is fed to the 65 machine from the feed bin 54 under the adjustable feed gate 57.

The feed flap 55, attached to the bin 54 rests upon the grizzly plate 56 which is secured to the muller frame 30.

When the pulley 5 rotates in the direction of the arrow A the muller plates 51 will rest upon the stationary rubbing surface 2 as shown in Figure 1, while the down stroke is taking place, the material from the bin 54 meantime feeding through the slots of the grizzly plate 56 and upon the surface 2.

At the end of the down stroke the action of the cam 11 will raise the muller frame 30 and the grizzly plate 56, raising the feed flap 55 and shutting off the feed from the bin 54 on the return or up stroke of the muller frame 30.

Any other feed construction may be used if desired provided it gives the results required.

When the cam 11 raises the muller frame 30 at the end of the down stroke, the cushions 50 come into contact with the flanges of the spindles 44 and cushion the impact as the mullers are raised from the surface 2.

At the end of the upstroke of the muller frame 30 the cam 11 lowers it again allowing the weight of the mullers once more to rest upon the material being treated on the stationary rubbing surface 2.

The path of the movement thus produced is 55 illustrated by the arrows indicated at C, Figure 1.

Should any extra large hard pieces, or a sledge hammer or other article in any manner find its way to the surface 2, the vertical self adjustment permitted by the brackets 32 and the hanger 33 will prevent damage to the upper end of the machine. And the vertical self adjustment permitted by the brackets 31 and the hanger 36 will prevent damage 100 to the lower end of the machine.

The adjustments permitted by the worm handle 29 and the spindles 44 will allow the machine and the individual mullers to be set to meet the requirements of any material or condition of operation.

The intermittent rubbing action of the mullers down the slope of the rubbing bottom 2 works the material fed from the bin 54 down to the lower discharge end 58 of the machine.

The material thus discharged, whose constituents have been disassociated by their passage down the surface 2 under the intermittent rubbing action of the mullers, is next put through the separation stage, in which the constituents are separated, as mentioned hereinbefore.

It is understood that the machine illustrated in Figure 1 is but one embodiment of the construction.

The construction by which the mullers are mounted may be varied as desired so long as the required results and operation are obtained.

In fact the muller mounting and construc-

tion shown in my former invention mentioned above may be employed if desired.

In any case the mullers should have a universal mounting so they may tilt as may be required by the material being treated, and they must have independent vertical self adjustment.

The mechanism shown for the reciprocation and elevation of the mullers may also be varied as desired, so long as the result is substantially one stroke with the mullers resting upon the surface 2 and followed by substantially one stroke with the mullers lifted from the surface 2.

15 In place of the cam and roller construction shown in Figure 1 any other proper construction may be used so long as the desired result is obtained. In fact the lifting construction shown in my former patent may be employed if desired, the lower end of the telescopic lifting rod being mounted on the crank pin 10 which operates the connecting rod 41, the upper end being pivotally mounted to actuate the bellcrank arms 16 and 34.

25 In any case the result should be that the mullers are lifted for substantially one stroke and are allowed to rest upon the surface 2 for substantially the following stroke.

30 As a variation of the above described dry method, and which makes my process all the more flexible to meet any case encountered, the material being treated may be sprayed with a liquid, either before or after it reaches the surface 2, and at any point in its progress 35 on the surface 2. This I call the moist method, and it may be used upon material already treated by the dry method, or upon the material discharged from the upper end of a machine operating by the wet method described hereinafter. In fact the dry, moist and wet methods may be used in any sequence 40 and combination that will produce the best results for any given case.

45 In Figure 2 are shown the variations in the machine when used wet with the separation stage of any portion of the material directly following the disassociation of its constituents.

50 The reciprocating and elevating mechanism shown in Figure 1, or any other mechanism, giving substantially the same operation may be used, except, as illustrated by the construction in Figure 1, the rotation of the pulley 5 will be in the direction shown by the 55 dotted arrow B.

This will produce a path of action for the mullers illustrated by the arrows D in Figure 2.

60 That is, when the muller frame 30 is moved on the out stroke, down the incline of the surface 2, the mullers 43 will be lifted; and when the muller frame 30 is moved on the instroke, up the incline of the surface 2, the mullers will be resting thereon.

65 When used wet, the tank is provided with

a lower end plate 59, held to the sides and bottom of the tank by the bolts 60 and nuts 61, the joint being water tight.

The lower end plate 59 provides an overflow edge 62, determining the level of the liquid in the tank and providing an overflow for liquid with which overflows the finer and softer constituents of the material being treated.

The action of the mullers working under water, together with the rest periods for settling of the material between the rubbing strokes of the mullers, tends to make not only a clean disassociation of the constituents of the material, but also a clean separation of them as well.

When more than one constituent of the material overflows from the tank, further separation thereof may be made by any of the well known methods; that is, when such constituents are of different specific gravity, have different settling rates, or different solubility, such differences may be used to make the further separations desired.

But, though the separation of the constituents of the material treated is a part of my process, it is not limited to the use of any particular separation method; for this reason such methods will not be described herein in detail.

The drain cock 63 is provided in the floor of the tank for use in draining same when the machine is used wet.

The feed in the wet method comes through the launder 64 to the distributor 65, and for this reason the bin 54 and the grizzly plate 56 are not required, though they are indicated in the plan view shown in Figure 3.

It will be noted that the grizzly plate 56 is not shown in Figure 2.

The uppermost mullers 66 are provided with transverse ribs 67 which act as rakes and move the harder material up the slope of the surface 2 above the water level and to the discharge lip 68.

Where desired, however, the uppermost mullers may be similar in construction to the other mullers; or the uppermost mullers may be provided with rubbing surfaces similar to the plates 51 for a portion of their extent and with rakes similar to the rakes 67 for other portions of their extent. The rake construction and the muller construction, and the proportion of one to the other being dictated by the case being considered at the time, experiment may be used to determine exactly what construction is best.

In Figure 2 it will be seen that the upper portion of the machine is provided with non-compressible rubbing surfaces of equal hardness, while the lower portion of the machine is provided with compressible rubbing surfaces of equal hardness. This combination of surfaces, which is different from the combination shown in Figure 1 gives further evi-

dence of the adaptability of my process and machine.

The same machine used in the wet process may be used in the dry method by a few simple changes as follows;—the lower end plate 59 is replaced by the cross piece 3'; the launder 64 and the distributor 65 are exchanged for the feed bin 54, feed flap 55, feed gate 57 and grizzly plate 56; and the uppermost rake 10 mullers 66 are exchanged for rubbing mullers 43. The direction of operation of the mullers is changed from that indicated by the arrows D in Figure 2, to that indicated by the arrows C in Figure 1, this change being accomplished 15 by merely reversing the direction of rotation of the pulley 5 from that indicated by the arrow B to that indicated by the arrow A.

In either the wet, the moist or the dry method the disassociation takes place through the intermittent rubbing action of the reciprocating and elevating mullers upon the material resting upon the stationary rubbing surface 2.

Because of the rest period between the rubbing strokes of the mullers the material supported on the surface 2 in the dry method will remain as it is left by the last contact of the mullers. With some materials and under some conditions this will give the results required to a greater extent than the dry method of my former invention where the lower rubbing surface performed substantially one stroke of its reciprocation during the period between muller contacts, during which stroke the particles of the material on the lower rubbing surface will tend to readjust their positions.

It would be difficult to state in advance which process and which machine and which rubbing surfaces and combination thereof would be best suited to any given substance or set of conditions and requirements; but between them all they furnish such a wide range of action that experiments can be depended upon to determine just what is best for any given case.

This may be especially true with such substances in which after disassociation of the constituents, one or more of them form into a cohesive mass in effect combining the disassociation and the separation stages as closely as they are combined with other substances in the wet method.

In the wet method, the rest period provided by my present process and machine, permits the agitated and suspended particles to settle upon the stationary surface 2.

This has a distinct advantage over the wet method of my former process and machine in some ways, and especially for some substances in which the harder constituents may tend to become suspended and overflow at the overflow edge 62 with the softer constituents.

There are however, certain advantages or points of difference, in the dry or the moist or the wet method of each process and in the machines for putting same into operation.

So, I do not claim that any method of either process or any machine is a cure-all that will properly meet every case, but I do believe my present process and machine to be a great improvement over my former process and machine under some conditions and requirements and with some substances, and that they offer increased adaptability for the solution of a milling problem.

I am aware of many changes and variations that any competent mechanic versed in such matters and in my two inventions would perceive, so I do not wish to limit my protection narrowly to the exact disclosures of the above specifications and the drawing, but what I claim as new and desire to protect by Letters Patent, is as follows:—

1. In a device for the disassociation of the separable constituents of a substance, including a stationary surface, a movable surface adapted to be reciprocated upon an outward and a return stroke and to rest upon the stationary surface during substantially one of said strokes, a frame adapted to be reciprocated and to raise and lower during such reciprocation, cushion means carried by the frame, and means carried by the movable surface and adapted to be engaged by said cushion means after a predetermined upward movement of the frame from its limit of travel.

2. In a device for the disassociation of the separable constituents of a substance, including support means, power means, two co-acting rubbing surfaces, and means driven by the power means and adapted to provide relative longitudinal movement between and intermittent separation of said surfaces including lifting means driven by the power means and adapted to have a substantially vertical reciprocating movement, cushion means carried by the lifting means, and means carried by one of the said surfaces and adapted to be engaged by said cushion means after a predetermined upward movement of the lifting means from its lower limit of travel.

3. In a device for the disassociation of the separable constituents of a substance, including support means, power means, a stationary rubbing surface, a movable rubbing surface adapted to be reciprocated upon an outward and a return stroke and to rest upon the stationary surface during substantially one of said strokes, a frame, means driven by the power means and connected to the frame to reciprocate same upon an outward and a return stroke, means driven by the power means and connected to the frame to provide substantially vertical reciprocation of the frame and to lift the frame during substantially

one of said strokes, cushion means mounted on the frame, and means carried by the movable surface and adapted to be engaged by the said cushion means after a predetermined upward movement of the frame from its lower limit of travel.

4. In a device for the disassociation of the separable constituents of a substance, including support means, power means, a stationary surface, a movable surface adapted to be reciprocated upon an outward and a return stroke and to rest upon the stationary surface during substantially one of said strokes, lifting means, means driven by the power means and connected to the lifting means to reciprocate same upon an outward and a return stroke, means driven by the power means and connected to the lifting means to provide substantially vertical reciprocation thereof and to lift said lifting means during substantially one of said strokes, cushion means mounted on said lifting means, and means carried by the movable surface and adapted to be engaged by the said cushion means after a predetermined upward movement of the lifting means from its lower limit of travel.

5. In a device for the disassociation of the separable constituents of a substance, including support means, power means, two co-acting rubbing surfaces, and means driven by the power means and adapted to provide relative longitudinal movement between and intermittent separation of said surfaces including lifting means driven by the power means and adapted to have a substantially vertical reciprocating movement, and a connection, universally resilient, between said lifting means and one of said surfaces adapted to lift said surface after a predetermined upward movement of the lifting means from its lower limit of travel.

6. In a device for the disassociation of the separable constituents of a substance, including support means, power means, a stationary surface, a movable surface adapted to be reciprocated upon an outward and a return stroke and to rest upon the stationary surface during substantially one of said strokes, lifting means, means driven by the power means and connected to the lifting means to reciprocate same upon an outward and a return stroke, means driven by the power means and connected to the lifting means to provide substantially vertical reciprocation thereof and to lift said lifting means during substantially one of said strokes, and a connection, universally resilient, between said lifting means and the movable surface and adapted to lift said surface after a predetermined upward movement of the lifting means from its lower limit of travel.

In testimony whereof I affix my signature.
THEODORE EARLE.
